UNITED STATES PATENT OFFICE.

WALLACE K. COATES, OF ST. LOUIS, MISSOURI.

BALL-FORGING MACHINE.

Application filed June 3, 1922. Serial No. 565,645.

To all whom it may concern:

Be it known that I, WALLACE K. COATES, a citizen of the United States, residing at St. Louis, in the county of St. Louis City and 5 State of Missouri, have invented new and useful Improvements in Ball-Forging Machines, of which the following is a specification.

The principal object of this invention is to 10 provide means for forming balls from hot cubes of metal by passing the cubes between a grooved roller and a pair of die blocks.

Another object of the invention is to provide means whereby the first die block has 15 a certain amount of movement to permit the cube to enter the space between the die block and the roller without cutting away any of the metal of the cube as the die block will accommodate itself to the irregular 20 shape of the cube or slug.

This invention also consists in certain other features of construction and in the combination and arrangement of the several parts, to be hereinafter fully described, illustrated in the accompanying drawings and 25 specifically pointed out in the appended claims.

In describing my invention in detail, reference will be had to the accompanying 30 drawings wherein like characters denote like drawings or corresponding parts throughout the several views, and in which:—

Figure 1 is a front view of the invention.

Figure 2 is a top view.

Figure 3 is a side view.

Figure 4 is a sectional view.

Figure 5 is a detail view showing the wedge means.

As shown in these views the frame of the 40 device is composed of a pair of side plates 1, which are spaced apart, the top plate 2 and the filler blocks 3 and 3^a, the parts being bolted together by the bolts 4. Each side plate is provided with an opening 5 which extends from the upper edge of the plate to 45 adjacent the center thereof with the bottom wall rounded. The walls of this opening are grooved, as at 6. The plate 2 is of substantially cross-shape so as to fit between the side plates and within the openings, the ends of each wing of the plate having projecting 50 parts 7 for engaging the outer edges and faces of the side plates, as clearly shown in Figure 2. In this way the upper ends of

the side plates are prevented from being 55 pressed outwardly. The top plate is secured to the side plate by means of the key bars 8, which pass through openings formed in the side plates and extend over the upper face of the top plate. These key bars are held 60 against longitudinal movement by the keys 9, which engage slots in the ends of said key bars. The grooved roller 10 is journaled in the side plates by means of the semi-circular bearing brasses 11 which engage the grooves 6 formed in the walls of the openings in said side blocks, the lower brasses fitting in the grooves in the bottom walls of said openings, as shown. The upper brasses are 65 formed with the bearing blocks 12, said 70 blocks having tongues engaging the grooves 6 and these blocks are held in position by the bolts 13 carried by the top plate. Associated with said grooved roller is a pair of 75 grooved die blocks 14 and 14^a arranged one above the other and fitting in the space formed by the side plates and filler blocks. The grooves in these blocks cooperate with the groove in the roller to compress the cubes, such as shown at 15, into a spherical 80 shape to form the ball 16. It will of course be understood that the groove in the upper block has its mouth made substantially wide to receive the cube and said groove gradually narrows until it reaches the size required. 85 It then continues at this size for about 60 degrees so as to give the ball a perfect shape and size. The groove then increases in size to permit the ball to drop out.

In order to permit the upper die block to 90 accommodate itself to the irregular shape of the slug and to prevent said die block from cutting away some of the metal of the slug I give said die block a certain amount of movement by providing recesses 17 in the 95 bottom of the top plate and the inner side of the vertical filler block 3^a to receive the rear and top edges of said die block. Thus the die block can move rearwardly and upwardly to increase the space between itself 100 and the top part of the roller and this amount of movement can be adjusted by the set bolt 18 carried by the top plate and projecting into the recess 17 therein and by the overlapping wedge pieces 19 which extend 105 into the side recess from openings in the side plates of the frame. These wedge pieces are movable one upon the other by the

screw 20 and the nut 21. I prefer to roughen the surface of the groove in the upper die block, as shown at 22.

I also place eye bolts 23 on the top plate 5 to permit the same to be lifted or put in place.

It will thus be seen that the cube is formed 10 into a ball with great economy and the metal ball has greater density insuring a sound ball uniformly round.

By having the upper die block movable 15 it will accommodate itself to the peculiar shape of the slug entering the space between itself and the roller, thus preventing tearing and cutting of the metal of the slug. By means of the wedge members and the bolt 18 the amount of movement of the die block can be adjusted. The said die block will normally remain in a position upon the 20 lower die block under the action of gravity.

It is thought from the foregoing description that the advantages and novel features 25 of my invention will be readily apparent.

I desire it to be understood that I may 30 make changes in the construction and in the combination and arrangement of the several parts, provided that such changes fall within the scope of the appended claims.

What I claim is:—

30 1. A ball forming machine comprising a frame, a grooved roller journaled therein, upper and lower die blocks supported by the frame and having grooves therein co-operating with the groove in the roller and means permitting the upper die block to have a certain amount of movement in a vertical and horizontal direction.

40 2. A ball forming machine comprising a frame, a grooved roller journaled therein, upper and lower die blocks supported by the frame and having grooves therein co-operating with the groove in the roller and adjustable means permitting the upper die block to have a certain amount of movement 45 in a vertical and horizontal direction.

3. A ball forming machine comprising a frame, a grooved roller journaled therein, upper and lower die blocks supported by the frame and having grooves therein co-operating with the groove in the roller to press a slug into spherical form, said frame having recesses therein for receiving the front and rear edges of the upper die block to permit movement of said die block.

55 4. A ball forming machine comprising a frame, a grooved roller journaled therein, upper and lower die blocks supported by the frame and having grooves therein co-operating with the groove in the roller to press a slug into spherical form, said frame having recesses therein for receiving the front and rear edges of the upper die block to permit movement of said die block and

means extending into said recesses for adjusting the amount of movement of said die block.

5. A ball forming machine comprising a frame consisting of a pair of side plates having openings in their upper portions and a top plate having portions fitting in said openings, a grooved roller having its shaft journaled in the lower walls of said openings, die blocks supported by the frame and having grooved edges for cooperating with the grooved roller to crush the blocks of metal into spherical shape when the roller is rotated.

6. A ball forming machine comprising a frame consisting of a pair of side plates having openings in their upper parts, the walls of the openings being grooved with the lower walls curved, a grooved roller supported in said frame, bearing brasses engaging the grooves in the side plates and embracing the shaft of the roller, bearing blocks for said brasses, a top plate for the frame, means detachably connecting the top plate to said side blocks and grooved die plates supported by the frame and cooperating with the grooved roller to press the metal blocks into spherical form when the roller is rotated.

7. A ball forming machine comprising a frame consisting of a pair of side plates having bearing openings therein, and a top plate having wings extending across the said openings, the ends of the plate and the wings having projections for engaging the edges and outer faces of the side plates, key means for locking the top plate to the side plates, a grooved roller having its shaft journaled in the lower part of the bearing openings and die blocks having grooves in their curved faces, for cooperating with the groove in the roller for forming the metal blocks into spherical bodies when the roller is rotated.

8. A device of the class described comprising a pair of spaced parallel side plates having aligned bearing openings formed therein, filler blocks secured to said side plates, a substantially cross shaped top plate disposed between said side plates and engaging said openings, key bars extending through said side plates above said top plate and provided with slots, keys engaging the slots in said bars, a pair of grooved die blocks arranged one above the other between said side plates and engaging said filler blocks, a shaft journaled in the bearing openings in said side plates, and a grooved roller secured to said shaft between said side plates and cooperating with the grooved die blocks aforesaid.

In testimony whereof I affix my signature.
WALLACE K. COATES.
